UNITED STATES PATENT OFFICE.

ELMER ELL WORTH BEEDE, OF PIPESTONE, MINNESOTA.

WATER-COOLING APPARATUS.

Application filed December 14, 1927. Serial No. 239,982.

This invention relates to improvements in water cooling apparatus in which the water to be cooled passes through a plurality of pipe coils arranged in a refrigerating chamber.

In certain lines of endeavor, amongst which may be mentioned the baking business, it is essential that a supply of water be constantly on hand of a certain degree of coolness, and any variation from this certain degree of temperature affects not only the working of the bread sponge but also the quality of the ultimate product. The objects of the present invention are, therefore, first, to provide a refrigerating chamber adapted to contain a cooling liquid in which the pipe coils are immersed; second, to provide means whereby the pipe coils are supported in the chamber spaced from the bottom thereof and from each other, so permitting a free circulation of the cooling liquid through and around the coils; and third, to provide storage means for the cooled water so connected with the pipe coils as to compel a constant circulation of the water through the said pipe coils and storage means and so ensure an even temperature of all the water in the system.

With these and certain other objects in view which will appear as the description proceeds, the invention resides in the novel construction, arrangement and combination of parts hereinafter first fully described in the following specification and later more specifically pointed out in the appended claim, reference also being had to the drawings forming part hereof, in which similar characters of reference indicate similar parts throughout the different views, and in which—

Fig. 1 is a side elevation of the apparatus with portions of the sides of the cooling chamber and storage tanks removed to show the interiors thereof.

Fig. 2 is a top plan view of the apparatus with portions of the tops of the cooling chamber and storage tank removed.

Fig. 3 is a fragmentary sectional elevation of the cooling chamber and water coils showing how the said coils are supported in the chamber.

Fig. 4 shows one of the supporting members apart from its connection with the coils.

In the drawings A indicates the cooling chamber of the apparatus as a whole and B the storage tank.

The chamber A is preferably constructed of galvanized iron or other suitable sheet metal in so far as the inner member 5 thereof is concerned, this member being shaped to form a container the interior of which is reached by means of a pipe 6 having a screw top cap 7.

The container 5 is surrounded in spaced relation, by a casing 8 of wood or other suitable material, and the space between the casing and container is filled with a suitable insulating medium 9, such for instance as cork.

10 and 11 indicate refrigerating members or coils of any of the well known automatically controlled electrically operated types. These coils are shown in the present disclosure as projecting into the container 5 at points adjacent the opposite corners of the same and sufficiently below the top of the said container as to be completely immersed in the liquid therein.

The number of refrigerating coils used determines the capacity of the installation, and this number may range from one upward, but when two are used the position shown is desirable as tending to give a more even cooling of the liquid in the tank and a better circulation of the said liquid through and around the said pipe coils.

The storage tank B is preferably of double construction, that is to say, it is formed with a tank 12 within a tank 13 of sufficiently larger dimension to afford an air space 14 between the two, the inner tank resting upon supports 15 upon the bottom of the tank 13 or being otherwise suitably supported therein.

16 indicates the inlet pipe through which water to be cooled is admitted to the system. The pipe 16 may connect with any suitable source of water supply under pressure, such as for instance as a city water works system, and it leads directly into the tank 12 at the top thereof, the water discharged from it being indicated by the numerals 17.

18 indicates a valve in the pipe 16 which is normally open but which may be closed to cut off the water supply in case of accident to any part of the apparatus.

19 indicates an outlet pipe leading from the upper part of the tank 12 to connect with the member 20 of the uppermost of the pipe coils in the container A. From the pipe 20 the water passes by way of the return elbows 21 and the pipes 22, 23, 24, 25, 26 and

27 across to the opposite side of the container, where, by way of the downwardly directed return elbow 28 it reaches the next series 29 of the pipe coils through which 5 it passes back across the container. This progress across and down of the water continues until it reaches the pipe 30, the lowermost and last in the series, which passes out through the side of the cooling chamber at 10 the point 31 and thence extends to discharge into the tank 12 at the point 32 adjacent the bottom thereof.

33 indicates a frost resisting liquid, preferably a mixture of alcohol and water, commonly called a "brine", with which the container is filled to completely submerge the refrigerating coils 10 and 11 and the pipe coils.

34 indicates as supporting member, several 20 of which may be used to support the lowermost of the pipe coils spaced from the bottom of the container 5, and others of which may be used to support the pipe coils above from each other, this being best shown in 25 Fig. 3. These supporting members serve to maintain the several pipe coils in horizontal position while permitting a free and unobstructed circulation of the cooling mixture under, through and around the said pipe coils. The members 34 may be made from 30 some easily manipulated metal bent to form loops and providing a series of semi-circular depressions in their sides properly spaced to receive the sides of the members of the several pipe coils.

The members 34 may be all alike and interchangeable as to their positions in the construction.

The outlet or service pipe 36 it will be 40 noted, draws from a point adjacent the bottom of the tank 12, so that the coldest water in the system will flow from the said pipe when the valve 37 is opened.

The action of the liquid 33 in the container 5 under the influence of the refrigerating coils 10 and 11 is too well understood to require much in the way of explanation, suffice it to say however, that a constant rise and fall or circulation of the said liquid 50 through and around the pipe coils in the container is set up by the influence of the refrigerating coils, the cooled liquid gravitating to the bottom of the container and absorbing the heat from the water in the

pipe coils on its return journey to the refrigerating coils.

The action of the water 17 in the system is precisely similar to that described for the liquid 33. As the water in the pipe coils is cooled by action of the liquid 33 and its specific gravity is increased it passes down through the pipe coils and, by way of the pipe 30, is discharged into the lower end of the tank 12, thus displacing the warmer and lighter water above which passes out of the tank and, by way of the pipe 19, reaches the member 20 of the pipe coils. As the circulation of the water is continuous it will be seen that but a very short time is required to bring all of the water in the system to an approximately even temperature, at which desired temperature, the thermostatic control feature of the refrigerating apparatus comes into operation to retain the water at the desired temperature.

Upon the periodical withdrawal of water from the system by operation of the valve 37, and the replacement of the same takes place by way of the pipe 16, the automatic control, always present in such systems of 80 refrigeration, can be relied upon to again permit the full operation of the refrigerating coils to quickly cool the more rapidly circulating water in the pipe coils.

The insulated construction of the cooling chamber A as described, and the provision of the air space around the tank 12 of the member B, are well calculated to prevent absorption of heat from the outside atmosphere by the liquid therein.

The provision of the tank B assures an ample supply of cooled water at all times, and at the same time ensures the circulation of the water through the entire system; two very desirable features.

Having thus fully described my said invention, what I claim is—

Water cooling apparatus comprising a suitably insulated container, a frost resisting liquid in the container, pipe coils immersed 100 in the liquid, a refrigerating element immersed in the liquid above the pipe coils, a storage tank for water, a pipe connecting the upper end of the tank with the uppermost of the pipe coils, and a pipe connecting 105 the lowermost of the pipe coils with the lower portion of the tank.

ELMER ELLSWORTH BEEDE.
